UNITED STATES PATENT OFFICE.

DOCK D. HARR, OF BELMOND, IOWA.

DESIGN FOR A BOTTLE.

SPECIFICATION forming part of Design No. 20,588, dated March 17, 1891.

Application filed February 10, 1891. Serial No. 380,984. Term of patent 14 years.

To all whom it may concern:

Be it known that I, DOCK D. HARR, a citizen of the United States, residing at Belmond, in the county of Wright and State of Iowa, ⁵ have invented and produced a new and original Design for a Bottle, of which the following is a specification, reference being had to the accompanying drawings, forming a part thereof.

10 Figure 1 is a front view of the bottle. Fig. 2 is a plan view, and Fig. 3 is a side view, of the bottle.

15 The bottle is provided with a flat back A and a curved front portion a. At the rear of the sides, where the curves of the front portion have ended, are two projecting ribs B, running the full height of the bottle and having their rear portions flush with the flat back of the bottle.

The neck C of the bottle is provided with ²⁰ the usual bead c around its top edge, and the rear side of the bead is placed in line with the flat back of the bottle. The upper part of the bottle is rounded off at c', so that there are no sharp projecting corners. ²⁵

What I claim is--

The design for a bottle herein shown and described, in which the bottle has a flat back, a curved front, and projecting side ribs flush with the back and extending the full height ³⁰ of the bottle, substantially as set forth.

DOCK D. HARR.

In presence of--

SAML. I. LINDSAY,
JOHN L. HARR.
